EARTH MOVING APPARATUS

Edward Albert Drott, Tomahawk, Wis.; Albert B. Houghton, Milton C. Drott, and John W. Drott, executors of the estate of Edward Albert Drott, deceased, assignors to Drott Manufacturing Corporation, a corporation of Wisconsin

Application January 15, 1954, Serial No. 404,275

12 Claims. (Cl. 37—117.5)

The invention relates to earth moving apparatus.

The main object of the invention is to provide an attachment for tractors and the like including a novel form of two-part bucket and its mounting whereby a great variety of earth-moving or working operations may be accomplished with one piece of equipment. More particularly, the present invention permits six different load handling operations to be accomplished, to wit: leveling and grading, shoveling by filling from the back, bulldozing, skid shoveling (filling from the front), back hoeing, and clam shell action.

The invention further consists in the several features hereinafter set forth and more particularly defined by claims at the conclusion hereof.

In the drawings:

Fig. 1 is a side elevation view of apparatus embodying the invention, the bucket being shown in dotted lines in a raised position;

Fig. 2 is a plan view of the apparatus;

Fig. 3 is a front elevation view of the apparatus;

Fig. 4 shows the bucket as positioned for conventional dumping;

Fig. 5 shows the bucket in another dumping position;

Fig. 6 shows the bucket positioned for bulldozing;

Fig. 7 shows the bucket positioned for loading as a conventional shovel;

Fig. 8 shows the bucket positioned for leveling and grading;

Fig. 9 shows the bucket in the loading position in which the front is filled by the plow action of the back;

Fig. 10 shows the bucket in back-hoeing position;

Fig. 11 shows the bucket in one of its clam shell positions;

Fig. 12 is a detailed view of the bucket positioning indicator;

Fig. 13 shows the bucket in a position for smoothing dirt;

Fig. 14 shows the bucket in a position for spreading dirt.

In the drawings the numeral 16 designates generally a tractor of known construction of the full crawler type having endless propelling treads 17 running over the usual front and rear sprockets and the rollers associated with the tread frames 18, the rear sprocket being driven from the rear axle 19. The treads 17 and their frames are spaced from the body 20 of the tractor which includes the usual engine, the transmission connecting the engine with the axle 19 and the driver's seat 21, and hydraulic supply and control equipment (not shown) for operating the rams or cylinders hereinafter described. The tractor may also be of the wheeled type without departing from the invention.

As herein shown, each tread frame has an upstanding bracket 22 providing a support for push beam or arm 23 pivotally connected to it at its rear end by a pin 24 and extending forwardly in the space between the body and the adjacent tread with its front end 25 extending outwardly in front of the tractor. Each front end 25 is provided with a ground engaging means or shoe 26.

2

Each beam 23 is adapted to be raised or lowered with the parts hereinafter described associated therewith by a double acting hydraulic cylinder 27 pivotally connected at its rear end by a pivot pin 28 to the bracket 22 and having a piston working in said cylinder with its rod 29 operatively connected to the intermediate portion of the arm 23 by a pivot pin 30. Each of the cylinders 27 has connections connecting its ends with a source of hydraulic pressure fluid so that its piston and the rod 29 may be moved in or out relative to the cylinder 27 or be hydraulically locked in a desired set position.

The shovel or bucket comprises a back 31 and a front 32, each of a width preferably equal to the width of the tractor or somewhat wider as shown.

15 The back 31 is formed of fabricated steel plates welded together and including a curved back plate 33, side or end plates 34, spaced sets of pivot plates 35, 36, and 37, and spaced bosses 38. The plates 35, 36, and 37 are pivotally connected by a pin 39 to the outer shoed end of one of the beams 23. The back plate 33 is shown as having a downwardly extending bulldozer blade end 40, but other forms of blade may be used with the front hereinafter described.

20 The front 32 is in the form of a scoop or bucket open at both ends and formed of fabricated steel plates welded together and including sides 41 and a bottom 42, the sides projecting beyond the rear edge of the bottom and adapted in the closed position of the bucket to overlap the end plates 34. The rear edge of the bottom has a cutting edge or knife 43 secured or formed integral with it, and the top edge of the bottom has a similar knife 44 secured or formed integral with it. The front has its sides pivotally connected to the upper end of the back 31 by pivot pins 45 mounted in the bosses 38 and in the sides 41 and spaced plates 46 secured to the front. The sides 41 and the plates 46 extend beyond the pivots to provide spaced arms 47 carrying pivot pins 48 forming connections for the rod ends 49 of hydraulic cylinders 50 whose back ends are pivotally connected by pins 51 to spaced sets of ears 52 secured to the back 31. The cylinders 50 are of the double acting type and through the arms 47 act to swing the front 32 toward or away from the back 31 or hold it in any desired position of angular adjustment relative to the back as determined by the setting of the control valves

64 or pointer which can be brought into line with any one of the indexed positions to set the bucket or its back in the desired working position.

The bucket is shown in Fig. 1 in a transporting or carrying position in which the pointer 64 is aligned with the first index position, the bucket then being free to be carried over the ground by the shoes 26 riding on the ground. If now, pressure liquid is introduced into the head end of the cylinder 53 to move the pointer 64 back to its second indexed position, the top of the back 31 of the bucket is swung ahead slightly so that the blade 40 is in ground contact and parts of the shoes 26 are in ground engaging position as shown in Fig. 8 for leveling and grading work, and the front 32 is then held in a raised position by its movement thereto by operation of the cylinder 50 to move its rod 49 inwardly as shown in Fig. 8. In this position the forward movement of the tractor causes the back 31 to smooth or level off the ground as it passes over it.

If, with the parts in the position shown in Fig. 8, more pressure liquid is introduced into the head end of the cylinder 53 to move the pointer to its fourth indexed position, the back 31 with its blade 40 is swung down to the position shown in Fig. 6 in which the shoes 26 are off the ground and the blade is in a position to act as a bulldozer, the front 32 being then in a raised position.

If the rod end 55 of the cylinder 53 is moved inwardly to bring the pointer 64 to its third indexed position, and the cylinder 50 is operated to swing the front 32 down to a position in which its lower blade 43 is in ground contact but spaced away from the blade 40 as shown in Fig. 9 and the tractor is moved forwardly, the earth is scooped up by the back 31 and thrown forwardly into the front 32 to load it, this type of action being preferable in some instances to a direct shoveling action by impact of the earth with the front end of the front 32. In this position the edge 43 acts as a depth gauge.

If, however, a conventional shoveling action is desired, the front 32 by the operation of the cylinders 50 is swung down to close the bucket, and the bucket is then tilted to the position shown in Fig. 7 by the operation of the cylinder 53, the pointer 64 then having been moved to its fifth indexed position.

For back-hoeing operation the front 32 is swung away from the back 31, and the back is tilted free of the ground as shown in Fig. 10, so that when the tractor is driven rearwardly, a back-hoeing operation is accomplished by the front, its lower blade 43 then being in contact with the ground. With the back in the position shown in Fig. 10 the pointer 64 is in line with the next to the last indexed position. For use of the bucket as a clam shell the back 31 is swung still farther forwardly from the position shown in Fig. 10 to the position shown in Fig. 11, in which case the pointer 64 is then in line with the last indexed mark, and then the front 32 on the operation of the cylinder 50 may be moved outwardly as shown to take a load between it and the back 31 and then be moved or swung toward the back to scoop up this load which may be earth, rock, logs, or other material that it is desired to lift.

In those operations above described, the filled bucket may be raised by the raising of the arms 23 to any dumping height up to the maximum, the dotted position of Fig. 1.

The filled bucket may be dumped in the conventional position shown in Fig. 4 by collapsing the cylinder 53. It is also desirable to be able to discharge the load as shown in Fig. 5 by collapsing cylinder 50 and swinging open the front 32. This allows more dumping clearance under the lowest position of the bucket and also facilitates the discharge of sticky materials.

Figs. 13 and 14 show the other positions of the bucket that may be used. In Fig. 13 the back 33 is in the same general angular position relative to the arms 25 as in

Fig. 11, but its edge 40 is in ground contact while the front 41 has been raised somewhat from that of Fig. 11, and in this position it may be used for smoothing dirt.

In Fig. 14 the shoes 26 are in ground contact while the back 31 has been tilted up from the position shown in Fig. 8 and as the machine proceeds in the direction of the arrow, dirt from the back is spread out in front of it.

It is to be noted that in Figs. 8 and 14 the arms 25 are in substantially the same position, but the back 31 is in different tilted positions relative to said arms to obtain different digging effects, the back being tilted or swung about the pins 39. Also the position of the arms for the operations shown in Figs. 7, 10, and 13 is the same, but the tilting of the back and the front relative to the arms brings about the different digging effects. Thus the control of the swing of the back of the bucket as a whole about the outer ends of the arms 25 is of importance.

While I have shown hydraulic cylinders 50 at each end of the back for swinging the front, I may also use a single hydraulic cylinder similar to one of the cylinders 50 and of requisite capacity centrally positioned relative to the bucket to perform the same function of controlling the front of the bucket. Also while the use of the lever 57 as a part of the linkage controlling the angular adjustment of the bucket back 31 is preferred, the bucket could be controlled by linkages other than shown or by direct connections to hydraulic cylinders.

I desire it to be understood that this invention is not to be limited to any particular form or arrangement of parts except in so far as such limitations are included in the claims.

What I claim as my invention is:

1. In a material handling apparatus, the combination with a vehicle, of a pair of arms swingingly mounted on the vehicle and projecting beyond one end thereof, means for raising and lowering said arms, shoes carried by the outer ends of said arms, a bucket having a back pivotally mounted on the outer ends of said arms and a front pivotally mounted at its upper end to the upper portion of said back, power operated means for adjusting the angular position of said back relative to said arms and shoes in the lowered position of said arms, and power operated means for angularly adjusting said front relative to said back so that a plurality of different types of material handling operations may be effected.

2. In a material handling apparatus, the combination with a vehicle, of a pair of arms swingingly mounted on the vehicle and projecting beyond one end thereof, means for raising and lowering said arms, a bucket having a back pivotally mounted on the outer ends of said arms and provided with a bottom blade and a front pivotally mounted on the upper portion of said back and having a blade at each end of its bottom, means for adjusting the angular position of said back relative to said arms in the lowered position of said arms, and means for angularly adjusting said front relative to said back so that a plurality of different types of material handling operations may be effected.

3. In a load handling apparatus, the combination of a movable supporting means, means for raising and lowering said supporting means, a bucket having a back pivotally connected at its lower end portion to said supporting means and provided with sides and a bottom blade and having a front pivotally connected to the upper portion of the back having a bottom and sides overlapping the sides of said back in its closed position and having a blade at the back end of its bottom in front of said overlapping sides and a blade at the front end of said bottom, means for positioning said back in different angular positions relative to said supporting means in the lowered position thereof, and means for angularly adjusting said front relative to said back.

4. In a load handling apparatus, the combination with a vehicle, of a pair of arms swingingly mounted on the vehicle and projecting beyond one end thereof, means

for raising and lowering said arms, a bucket having a back pivotally mounted on the outer ends of said arms and a front pivotally mounted at its upper end to the upper portion of said back, power operated means for adjusting the angular position of said back relative to said arms in the lowered position of said arms and power operated means for angularly adjusting said front relative to said back so that a plurality of different types of material handling operations may be effected.

5. Load handling apparatus as defined in claim 4 10 wherein the back has a bottom blade.

6. Load handling apparatus as defined in claim 5 wherein the projected ends of the arms have ground engageable shoes.

7. In a material handling apparatus, the combination 15 with a vehicle, of a movable supporting means, a bucket having a back pivotally connected to said supporting means and provided with a blade at its lower end, a front pivotally mounted at its upper end to the upper portion of said back and having a blade at its leading edge, power means for angularly adjusting said back relative to said supporting means in the lowered position of said supporting means, and power means for angularly adjusting said front relative to said back.

8. In a load handling apparatus, the combination of 20 a tractor vehicle, supporting means pivotally connected to said vehicle and extending beyond one end thereof, a bucket including a back pivotally mounted substantially at its lower end on the extended end of said supporting means and a front pivotally connected at its upper end to the upper portion of said back, power operated means for raising and lowering said supporting means, power operated means for tilting said back relative to said supporting means in the lowered position of said supporting means, and power operated means for tilting said front relative to said back.

9. Load handling apparatus according to claim 8 in 25 which the supporting means are a pair of arms having ground engaging shoes at their extended ends adjacent the pivotal connection of said back with said supporting means.

10. Load handling apparatus as defined in claim 8 in 30 which the front in its closed position relative to the back forms therewith a shovel and in which the front has a lowered open position relative to the back to form a back hoe.

5

11. In a load handling apparatus, the combination with a vehicle, of a pair of arms swingingly mounted on the vehicle and projecting beyond one end thereof, means for raising and lowering said arms, a bucket having a back member and a front member each including a top and a bottom, said back member being pivotally mounted on the outer ends of said arms and said front member being pivotally mounted on said back at a position substantially above the bottom of each of said members for movement of the bottom of said front member into and out of closing relation with the bottom of said back member, power operated means for adjusting the angular position of said back relative to said arms in the lowered position of said arms, and power operated means for angularly adjusting said front relative to said back so that a plurality of different types of material handling operations may be effected.

12. In a material handling apparatus, the combination 20 with a vehicle, of a movable supporting means, a bucket having a back member and a front member each including a top and a bottom, said back member being provided with a blade at its bottom and being pivotally mounted on said supporting means and said front member being provided with a blade at its leading edge and being pivotally mounted on said back at a position substantially above the bottom of each of said members for movement of the bottom of said front member into and out of closing relation with the bottom of said back member, power means for angularly adjusting said back relative to said supporting means in the lowered position of said supporting means, and power means for angularly adjusting said front relative to said back.
